No. 799,393.

PATENTED SEPT. 12, 1905.

R. M. LOVEJOY.
CIRCUIT BREAKER FOR EXPLOSIVE ENGINES.
APPLICATION FILED JAN. 30, 1905.

UNITED STATES PATENT OFFICE.

RALPH M. LOVEJOY, OF MEREDITH, NEW HAMPSHIRE.

CIRCUIT-BREAKER FOR EXPLOSIVE-ENGINES.

No. 799,393.

Specification of Letters Patent.

Patented Sept. 12, 1905.

Application filed January 30, 1905. Serial No. 243,268.

To all whom it may concern:

Be it known that I, RALPH M. LOVEJOY, a citizen of the United States, and a resident of Meredith, in the county of Belknap and State of New Hampshire, have invented a new and Improved Circuit-Breaker for Explosive-Engines, of which the following is a full, clear, and exact description.

My invention relates to circuit-breakers and admits of general use, but is peculiarly applicable upon explosive-engines and in analogous relations where it is desirable to break the circuit quickly and positively and at a comparatively high frequency—as, for instance, in setting up powerful secondary currents used to ignite explosive charges by its spark.

Reference is to be had to the accompanying drawings, forming a part of this specification, in which similar characters of reference indicate corresponding parts in all the figures.

Figure 1 is a side elevation, partly diagrammatic, showing my invention as applied to an explosive-engine. Fig. 2 is a front elevation of the casing containing the contact mechanism, the glass plate of the casing and the ring for holding the plate in position being removed for the sake of clearness. Fig. 3 is a vertical section on the line 3-3 of Fig. 2 looking in the direction of the arrow and showing the contact-lever, the rocking arm below it, and the crank mechanism for actuating the rocking arm and the contact-lever; and Fig. 4 is a vertical central section through the contact-lever, showing the contact-bosses used in making and breaking the circuit and also showing the insulation of certain of these bosses.

The body of the engine is shown at 5, and connected with the engine in the usual manner are the secondary wires 6 7, in which it is desired to develop high differences in potential for the purpose of causing the spark to jump within the explosion-chamber in a manner well understood in this art.

The induction-coil or transformer is shown at 8 and need not be provided with an interrupter. A battery 9 is connected by a wire 10 with the primary of the induction-coil or transformer, and from the battery a wire 11 leads to the pivot 21 of a contact-lever hereinafter described. Another wire leads from the primary winding of the transformer 8 to a contact-arm 12^a, the latter being provided with a cam-surface 12^b, as will be understood from Fig. 2. A gear-wheel 13, carried by a

shaft of the engine, meshes with another gear-wheel 14, whereby the latter is rotated. This wheel 14 is mounted upon a shaft 18, which is provided with a crank 19, having at its outer end a roller 20. When the shaft 18 rotates, the roller 20 is brought successively into and out of engagement with the cam-surface 12^b, so as to alternately raise and lower the rocking arm 12^a, which normally rests upon a stop-pin 12^c. A casing 15 is provided internally with an annular member 16, of insulating material, and is provided also with a plate 17, of transparent material, such as glass, this plate being held in position by an annular cap 17^a. The pivot-pin 21 passes through the back of the casing and serves partly as a binding-post for the wire 11 and partly as a pivot for a contact-lever 22. This contact-lever is provided with an eye 24, through which the pivot-pin 21 is threaded, for the purpose of allowing the movement just mentioned. Contact-posts 25 26 are provided with conical portions 27 28, projecting downwardly and constituting contact-surfaces. Similar contact-posts 29 31 are provided with conical portions 30 32, serving as contact-surfaces. The posts 29 31 are insulated by means of washers 33 34, of insulating material, preferably of hard rubber. A plate 33^a, of hard rubber, is disposed upon the under side of the contact-lever 22 and is engaged by the conical members 27 28 30 32, being thereby held in position.

As will be seen in Figs. 2 and 4, the conical members 28 and 30 constitute the contact-surfaces of the posts 26 and 29 and are a little larger and longer than the conical members 32 and 37. This discrepancy in the sizes of the conical members is for the purpose of giving the series of conical members a sort of curvature, so as to readily enable them, considered as a whole, to rock upon an independent surface.

The rocking arm 12^a is flattened upon its upper surface and is adapted to be engaged by the conical contact members one at a time, as will be understood from the full and dotted lines shown in Fig. 2.

Integral with the contact-lever 22 is an arm 35, tensioned by means of a spiral spring 36, the latter being adjustable by means of a screw 37, engaging a bracket 38, the latter being rigidly connected with the casing and insulated therefrom.

The operation of my device is as follows: The shaft 18 being rotated, the crank 19

causes the roller 20 to alternately raise and lower the rocking arm 12^a, and the upper surface of this arm alternately engages and disengages the several conical contact members 5 27 30 28 32. The members 27 28 being in electrical communication with the contact-lever 22 are adapted to open and close electrical communication between the contact-lever and the rocking arm 12^a, whereas the members 32 30, while preferably metallic, as shown, are in reality insulating members and serve merely to prevent the members 27 28 from simultaneously engaging the rocking arm 12^a. The result is that the contact-lever 10 22 being in its uppermost position, as indicated by full lines in Fig. 2, the battery-current is free to flow through the following circuit: battery 9, wire 11, pivot-pin 21, contact-lever 22, post 25, conical contact member 27, rocking arm 12^a, wire 12, primary winding of coil 8, wire 10, back to battery 9. The rocking arm 12^a being now slightly lowered by a partial rotation of the cam, the circuit above described is broken between the conical member 27 and the rocking arm 12^a, because the insulated contact member 30 now supports the tension of the lever 22. The rocking arm 12^a being lowered still farther, the conical contact member 28 is brought into engagement 15 with the rocking arm 12^a, and another circuit is completed similar to that above traced, with the exception that the contact member 28 instead of the contact member 27 is affected. The rocking arm 12^a being lowered still farther, the insulated member 32 supports the tension of the contact-lever 22. It follows, therefore, that each revolution of the cam 19 makes and breaks the circuit as many times as there are contact members 27 28 in communication with the lever 22 and insulated contact members 30 32 for breaking communication.

While I show and preferably use two contacts of each kind, I do not limit myself to this number, as obviously any other number can be employed, according to the nature of the work; neither do I limit myself to the particular shape or form of any of the parts nor to the exact arrangement of mechanism 45 shown in the device as a whole.

Having thus described my invention, I claim as new and desire to secure by Letters Patent—

1. In a device of the character described, the combination of a contact-lever studded with 50 contact-points, some of which are insulated from said lever and others in electrical communication therewith, a part engaging with and disengaging from said contact-points, and electrical connections for said lever and said 55 part.

2. In a device of the character described, the combination of a contact-lever studded with contact-points spaced apart and in electrical communication with a common source of electricity, a plurality of insulated members dis-

posed intermediate of said contact-points, a member of conducting material adapted to engage with and disengage from said contact-points and also adapted to engage with and disengage from said insulated members, means 70 for moving said contact-lever relatively to said member of conducting material, electrical connections extending to said contact-lever and to said member of conducting material, and a spark-coil and source of electricity connected 75 with said electrical connections.

3. In a device of the character described, the combination of a rocking arm, means for actuating the same, a rocking lever disposed adjacent to said arm, and contact members in 80 electrical communication with said rocking lever, said contact members being adapted to engage and disengage said rocking arm.

4. In a device of the character described, the combination of a crank, a rocking arm to be 85 actuated by movements thereof, a conducting member disposed adjacent to said rocking arm and provided with contact members to be engaged with and disengaged from said rocking arm, electrical connections leading from said 90 conducting member and said rocking arm to mechanism to be energized, and means for tensioning said rocking arm.

5. In a device of the character described, the combination of a conducting member provided 95 with a plurality of contact-points projecting therefrom, a plurality of projecting insulated members disposed alternately with said contact-points, a rocking arm provided with a surface to be engaged by said contact-points 100 and by said insulated members, said contact-points and said insulated members projecting to different extents for the purpose of preventing all of said contact-points and all of said insulated members from engaging said surface of said rocking arm at the same time, means for actuating said rocking arm, electrical connections for said rocking arm and said conducting member, and spring mechanism 105 engaging said conducting member. 110

6. In a device of the character described, the combination of a conducting member adapted to rock, a spring for retracting said conducting member, a plurality of contact members connected with said conducting member and projecting therefrom, a plurality of insulated members disposed alternately with said contact members, said insulated members and said contact members projecting to different extents from said conducting member, a part to 115 be engaged by said contact members and by said insulated members, means for moving said conducting member relatively to said part, and electrical connections for said part and for said conducting member. 125

7. In a device of the character described, the combination of a revoluble shaft, a crank mounted thereupon and provided with a roller, a rocking member provided with a cam-surface to be engaged by said roller, an electrical 130

connection for said rocking member, a contact-lever disposed above said rocking member and also free to rock, means for retracting said contact-lever, an electrical connection for said contact-lever, a plurality of contact-points in electrical communication with said contact-lever, a part to be engaged by said contact-points, and members of insulating material disposed intermediate of said contact-points for the purpose of preventing

a plurality thereof from simultaneously engaging said rocking arm.

In testimony whereof I have signed my name to this specification in the presence of two subscribing witnesses.

RALPH M. LOVEJOY.
